(57) **CLAIM**

The ornamental design for a material testing machine with voice control function as shown and described.

DESCRIPTION

FIG. 1 is a perspective view of a material testing machine with voice control function showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing the solid-lined portion thereof;

FIG. 9 is a front view showing the solid-lined portion thereof;

FIG. 10 is a rear view showing the solid-lined portion thereof; and,

FIG. 11 is a side elevation view showing the solid-lined portion thereof.

The broken lines in FIGS. 1-7 depict portions of the material testing machine with voice control function that form no part of the claimed design.
